Sturtevant Marion

Atty's.

UNITED STATES PATENT OFFICE.

THOMAS L. TALIAFERRO, OF CHICAGO, ILLINOIS, ASSIGNOR TO PHOENIX-HERMETIC COMPANY, OF CHICAGO, ILLINOIS, A CORPORATION OF NEW YORK.

SEALING BAND FOR JARS.

Application filed July 5, 1927. Serial No. 203,563.

The invention relates to new and useful improvements in separable sealing bands for jars or the like, and more particularly to a sealing band having on one end thereof a 5 projecting tab with an opening therethrough, and on the other end thereof, a locking tongue which projects through said opening and is folded against the outer face of the tab.

An object of the invention is to provide 10 a sealing band of the above type with reinforcing ribs extending lengthwise of the tab which project outwardly and serve to house the locking tongue and prevent the same from being caught and bent so as to release the 15 band.

In the drawings which show by way of illustration one embodiment of the invention—

Figure 1 is a side view of a sealing band embodying the improvements shown applied 20 to a jar;

Fig. 2 is an enlarged sectional view through the band on the line 2—2 of Fig. 1, and

Fig. 3 is an enlarged sectional view through the band on the line 3—3 of Fig. 1.

25 It has been very common in the art to provide a separable sealing band for sealing jars. The band includes a body portion having an overlying flange which engages the closure, and the lower edge portion of the band is 30 bent or crimped underneath the ledge on the jar for sealing the jar. At one end of the band, there is a projecting tab which is provided with an opening therethrough, while on the other end of the band, there is a locking tongue which extends through the opening 35 and thus locks the ends of the bands together.

The present invention is directed to the 40 construction of the tab at one end of the sealing band. The tab in the present embodiment of the invention includes a reinforcing raised rib which extends from a point adjacent the base of the tab at one edge thereof, around the edge to a point adjacent the base 45 at the other edge thereof. This reinforcing rib is spaced from the edge and serves the double function of reinforcing the tab so that when it is raised, it will, with certainty, lift the locking tongue and release the parts of 50 the sealing band, and of housing the locking tongue so as to prevent it from being caught by any object rubbing along the surface of

the band, and thus the sealing band released unintentionally.

Referring in detail to the drawing, the invention is shown as embodied in a sealing band consisting of a body portion 1 having a flange 2 which overlies the closure indicated at 3 in Fig. 2 of the drawing. The lower portion 4 of the band is adapted to be spun underneath a ledge or shoulder 5 formed in the jar which is indicated at 6 in the drawing. One end of the band is provided with a projecting tab 7. This tab is formed with an opening 8 extending transversely across the tab and adjacent the base of the tab, that is, where the projecting tab joints the end of the band. The other end of the band is provided with a locking tongue 9 which is adapted to extend through the opening 8 and be folded 65 back against the outer face of the tab. The tab is provided with a reinforcing raised rib 10. This rib 10 is spaced from the edge of the tab and extends from the point 11 adjacent the base at one edge or side of the tab along 70 the edge of the tab, around the end thereof, and then along the other side of the tab to the point 12 which is adjacent the base of the tab. This reinforcing rib as it extends from the point 11 around to the point 12, extends 75 on three sides of the locking tongue 9. The rib is raised so that the outer edge of the rib lies in a plane outside of the folded down tongue 9. Any object moving along the band in contact with the rib 10 will pass over the 80 tongue without engaging the end thereof and raising the same.

This reinforcing rib 10 performs the double function, therefore, of reinforcing the tab, so that when the free end of the tab is raised by 90 the thumb or finger, the whole tab will bend about the axis at the base of the tab rather than intermediate the length of the tab. When the tab bends about the axis at the base thereof, that is, along the line $x-x$, of Fig. 1, it will raise the tongue 9, and this will release the connected ends of the sealing band. The second function of this raised rib is to house the tongue so as to prevent its being caught and unintentionally released by the 95 object passing along the surface of the band.

It is obvious that minor changes in the details of construction and arrangement of the parts may be made without departing from

the spirit of the invention as set forth in the appended claims.

Having thus described the invention, what I claim as new and desire to secure by Letters Patent, is—

- 5 1. A separable sealing band for jars comprising a body portion having a flange adapted to overlie the closure and a portion adapted to be turned underneath the jar ledge, one end of said band having a projecting tab provided with an opening therethrough, and the other end of said band having a locking tongue adapted to extend through said opening and be folded against the outer face of the tab, said tab having a raised reinforcing rib extending lengthwise thereof for housing the tongue and reinforcing said tab, said tongue being of lesser length than the reinforcing rib so that the latter can protect it 10 from unintentional lifting.
- 15 2. A separable sealing band for jars com-

prising a body portion having a flange adapted to overlie the closure and a portion adapted to be turned underneath the jar ledge, one end of said band having a projecting tab 25 provided with an opening therethrough, and the other end of said band having a locking tongue adapted to extend through said opening and be folded against the outer face of the tab, said tab having a raised reinforcing rib 30 extending from a point adjacent the base of the tab at one side thereof along the edge of the tab, around the end of the tab, and to a point adjacent the base of the tab at the other side thereof, said tongue being 35 of lesser dimensions than the area enclosed by said rib, said rib being spaced back from the edge of the tab and located outside of the locking tongue passing through the tab so as to house said locking tongue.

40 In testimony whereof, I affix my signature.

THOMAS L. TALIAFERRO.
